NICHOLAS S. VEDDER, OF TROY, AND TOBIAS S. HEISTER, OF LANSINGBURG, NEW YORK, ALSIGNORS TO NICHOLAS S. VEDDER.

Design No. 3,862, dated February 22, 1870.

DESIGN FOR A STOVE-PLATE.

The Schedule referred to in these Letters Patent and making part of the same.

To all whom it may concern:

Be it known that we, NICHOLAS S. VEDDER, of Troy, and TOBIAS S. HEISTER, of Lansingburg, in the county of Rensselaer, and State of New York, have jointly invented and produced a new and original Design for Plates of a Stove, of which the following is a specification, reference being had to the accompanying photographic illustration.

Our new design for the bottom plate *p*, front plate *q*, end plate *r*, top plate *s*, and cover *t* of a stove, is represented in the aforesaid photograph.

What we claim as our invention or production, and desire to protect by Letters Patent, is—

The design for the above-named plates or parts of a stove, as shown in the aforesaid photographic illustration.

NICHOLAS S. VEDDER.
TOBIAS S. HEISTER.
